BEVERAGE DISPENSER

Martelle J. Syverson, Albert Lea, Minn., assignor to Fountain Industries, Inc., Albert Lea, Minn., a corporation of Iowa

Filed July 10, 1967, Ser. No. 7,735

Term of patent 14 years

Int. Cl. D15—12

U.S. Cl. D94—3

FIG. 1 is a frontal perspective view of a beverage dispenser showing my new design;

FIG. 2 is a top plan view thereof;

FIG. 3 is a frontal elevational view thereof;

FIG. 4 is an elevational view thereof taken from the end as seen from the right of FIG. 3, the opposite end being a mirror image thereof;

FIG. 5 is a cross-sectional view thereof taken along line 5—5 in FIG. 3; and

FIG. 6 is a cross-sectional view thereof taken along line 6—6 in FIG. 3.

The rear of the beverage dispenser is substantially flat and plain in appearance.

I claim:

The ornamental design for a beverage dispenser, substantially as shown and described.
